(57) **CLAIM**

The ornamental design for a baking mold, as shown and described.

DESCRIPTION

FIG. 1 is a top perspective view of a baking mold showing my new design;

FIG. 2 is a bottom perspective view thereof;

FIG. 3 is a left side view thereof;

FIG. 4 is a top view thereof;

FIG. 5 is a front view thereof;

FIG. 6 is a rear view thereof;

FIG. 7 is a bottom view thereof; and,

FIG. 8 is a right side view thereof.

The broken lines shown in the drawings depict portions of the baking mold that form no part of the claimed design.
